UNITED STATES PATENT OFFICE.

EZRA DIXON, OF BRISTOL, RHODE ISLAND.

TOP-ROLL SADDLE.

SPECIFICATION forming part of Letters Patent No. 757,727, dated April 19, 1904.

Application filed October 16, 1902. Serial No. 127,548. (No model.)

To all whom it may concern:

Be it known that I, EZRA DIXON, a citizen of the United States, residing at Bristol, in the county of Bristol and State of Rhode Island, have invented a new and useful Improvement 5 in Top-Roll Saddles, of which the following is a specification.

This invention has reference to an improvement in the top-roll saddles and weight-straps 10 used on spinning-machines.

The object of the invention is to connect the weight-strap flexibly with the saddle and provide means for adjusting the weight-strap on the saddle.

15 To this end the invention consists in the peculiar and novel construction more fully set forth hereinafter.

The top-roll saddles of spinning-machines have to be from time to time removed and the 20 bearing-point of the strap readjusted to regulate the pressure of the front top roll on the sliver passing between the rolls. In this removal it is desirable to have the weight-strap flexibly connected with the saddle and to have 25 means for accurately adjusting the bearing of the weight-strap on the saddle.

In my present invention I provide the front top-roll saddle with a slot and an adjusting-screw and provide the weight-strap with a 30 contracted neck, by which the weight-strap may be flexibly secured with the saddle.

Figure 1 is an end view showing the front and rear top-roll saddles bearing on the journals of the drawing-rolls and the front saddle 35 provided with an adjusting-screw bearing against the weight-strap. Fig. 2 is a top view, partly in section and on an enlarged scale, showing the weight-strap connected with the saddle and bearing against the end 40 of the adjusting-screw. Fig. 3 is a transverse sectional view showing the connection of the weight-strap with the front top-roll saddle.

In the drawings, *a* indicates the front top-roll saddle; *b*, the rear saddle; *c c*, the top rolls; 45 *d*, the weight-strap; *a'*, a slot extending through the front top-roll saddle, and *a²* a screw in screw-thread engagement with the front end of the top-roll saddle provided with the head *a³*. The weight-strap is provided with the 50 contracted neck *d'* below the head *d²* and may be inserted into the slot *a'* and then turned

into the position shown in Fig. 2, thereby connecting the weight-strap flexibly with the front top-roll saddle. The upper surface of the front top-roll saddle is usually inclined toward 55 the front, as is shown in Fig. 1, and the weight-strap bears against the end of the screw *a²*. By adjusting this screw the weight-strap may be adjusted longitudinally on the saddle farther from or nearer to the front top roll, and 60 thereby the pressure on the front roll may be regulated. The saddle may be provided with the transverse ridge *a⁴*, by which the turning of the weight-strap in the slot *a'* is 65 limited and the disconnection of the weight-strap of the saddle prevented.

In the ordinary or normal use, as shown in the drawings, the weight-strap cannot be removed from the saddle even when the ridge *a⁴* is omitted, because the head *d²* of the 70 weight-strap cannot be passed through the slot *a'* with the screw *a²* in the position shown in Fig. 2.

By my improved construction of the front top-roll saddle and the weight-strap the position of the weight-strap may be adjusted 75 while the spinning-machine is in operation by inserting an ordinary screw-driver into the slot in the head *a³* and turning the screw.

As the bite of the front top drawing-rolls 80 controls the delivery of the sliver to the spinning-spindle, the adjustment of the weight bearing on the front top-roll saddle while the machine is running facilitates the control of the delivery of the sliver, enabling the operator 85 to change the adjustment and watch the result of such change.

Having thus described my invention, I claim as new and desire to secure by Letters Patent

In a top-roll saddle, the combination with 90 a weight-strap *d*, the head *d²* of the weight-strap and the contracted neck *d'* below the head, of the saddle *a* provided with the slot *a'*, and the screw *a²* adapted to adjust the position of the weight-strap, as described. 95

In testimony whereof I have signed my name to this specification in the presence of two subscribing witnesses.

EZRA DIXON.
